INVENTOR

UNITED STATES PATENT OFFICE.

JAMES G. HARDIE, OF CANTON, NEW YORK.

SHEET-CARRYING MECHANISM.

1,310,618.

Specification of Letters Patent.

Patented July 22, 1919.

Application filed March 29, 1918. Serial No. 225,395.

To all whom it may concern:

Be it known that I, JAMES G. HARDIE, a citizen of the United States of America, and a resident of Canton, county of St. Lawrence, and State of New York, have invented certain new and useful Improvements in Sheet-Carrying Mechanism, of which the following is a specification.

The present invention relates to improvements in a sheet-carrying mechanism for printing presses and the like, in which a bank of sheets is fed singly to a cylinder press or other sheet-handling mechanism.

The object of this invention is to provide means to move a bank of sheets forward intermittently while the single sheets are fed off, without stopping the press.

The following are some of the new features of this invention:

- 20 (a) A main feed-table having belts passed around it to carry forward the stock.
- (b) A spring-adjusting member to keep the belts constantly taut.
- (c) A member contacting the type-bed of the press to ratchet the belts forward.
- (d) A cover to protect the paper from the moist atmosphere.

The accompanying illustrations show the invention mounted upon a printing press; although it may be used in connection with other kinds of machines to which sheets are singly fed.

Similar numbers refer to similar parts throughout the drawings.

Referring to the various figures, which are as follows:

General form of construction.

In Figure 1 is shown a general construction of my invention, mounted upon a printing press of any well-known type. The feed-table is extended backward to whatever length may be desired. Upon the rear of this feed-table is mounted a tail-board which enables the operator, when loading the stock, to push an armful of stock across the feed-table, upon the smooth tail-board, without the stock's contacting the belts, which, if contacted by the stock, will mar and damage the stock, as well as to impede the loading of the stock, especially when putting up the first lift.

In the front end of the feed-table is journaled a shaft carrying belt-pulleys and a ratchet; belts are passed around the feed-table, below the tail-board, and over pulleys

which are journaled in each end of the feed-table.

During damp or dry weather, these belts are kept at a practical tautness with the aid of the spring-adjustable, rear-bearing.

A depending arm may be either pivotally attached to the press-frame direct, or it may be attached to the bottom of the feed-table. This arm has a foot pivotally attached to it and adapted to be swung upwardly out of the pathway of travel of the type-bed, so that the mechanism will be dormant only when it is desired to move the bank of stock forward. This foot is so designed with an extended end that when it is allowed to fall, it will become operative in connection with the arm to which it is pivoted, and thus swing the arm backward while the foot contacts the moving type-bed. The whole construction of the arm and its connection is such, that, by gravity, they will return to the desired position whenever the type-bed moves forward.

The foot-treadle is so located as to be convenient for the feeder to reach it with his foot, so as to make the whole mechanism operative without interfering with the constant feeding of the sheets by hand, as the stock is moved forward while the press is kept working.

A roll of flexible material is suitably journaled in the rear of the tail-board to cover the stock which is piled upon the feed-table, especially when the stock lies, unused, over night, when the atmosphere is laden with moisture. This covering may be rolled up, as illustrated, when the press is in operation.

Description of parts in detail.

95

Fig. 1, A is the press-frame, B is the impression cylinder, C is the type-bed, D is the feeder's seat; 1 is the main feed-table which is rigidly attached to the press-frame, the rear end of which is supported by the braces 2, which are attached to the press-frame and to the feed-table; 3 is a depending arm pivotally attached to the press-frame; 4 is a foot pivotally attached to the arm 3; 5 is a treadle pivotally attached to the press-frame, and normally held in an elevated position by the counter-weight 6; 7 is a flexible member passing over the roll 8 and connecting the treadle 5 with the foot 4 which normally holds the foot out of the path of travel of the type-bed C; 9 is a link

connecting the arm 3 and the arm 10 which are pivotally mounted upon the shaft 11 which is journaled in the front end of the feed-table 1; 12 is a ratchet rigidly mounted upon the shaft 11; 13 is a pawl pivotally mounted on the arm 10 and engages the ratchet 12; 14 is a plurality of belts which passes around the feed-table 1 and over the pulleys 15 which are mounted upon the shaft 11, and 10 also passes around the pulleys 16 which are journaled in the movable bracket 17 mounted upon the threaded rod 18 which is slidably mounted in the bracket 19 which is rigidly attached to the bottom side of the feed-table. Upon the threaded rod 18 is a compression-spring 20 and an adjusting-nut 21; 22 are guides fastened to the bottom side of the tail-board between which the bracket 17 slides. 20 Fig. 1, 24 is a flexible cover wound upon a shaft journaled in the brackets 25, which may be fastened to the tail-board or to the feed-table as desired, so long as the roll is behind the tail-board, in order not to be in 25 the way of loading the stock. This flexible cover should preferably be wider than the stock so as to hang over the edges to securely protect the stock from its gathering moisture, and thus shrink the stock, especially 30 when it is piled upon the feed-table over night.

Fig. 2, is an end view of the rear belt-pulleys showing the guides 22 on either side of the bracket 17, which contacts the tail-board to be kept in position.

Fig. 3 is a plan view showing the various parts described and illustrated in Figs. 1 and 2.

Manner of operation.

40 The stock is loaded by commencing at the rear of the table, pushing a folded lift of sheets upon the tail-board, across the feed-table, and then to open the folded lift out 45 flat. The successive lifts are then laid forward upon the first lift until the feed-table is loaded to a certain depth its entire length. As the sheets are then fed singly to the press and it becomes necessary to move the bank 50 forward, to be within easy reach of the operator, he presses the pedal with his foot, which has the effect to allow the foot 4 to take a perpendicular position and thus fall in the pathway of travel of the type-bed, 55 which has the effect to rock the arm 3 backward, and, by gravity, or by a spring if desired, the arm will return to its forward position again to be moved backward by the bed, and through the intervening parts of 60 links, pawl, and ratchet the front shaft carrying the sheets will be intermittently rotated, thus bringing the bank of stock forward to the desired position. Then, as the 65 operator removes his foot from the pedal, which is sufficiently counter-weighted, it

will again raise the foot on the depending arm up out of the pathway of the type-bed.

When fabric is used for belting, it is liable to shrink whenever the atmosphere is damp, and whenever the air is dry the belts will 70 stretch; hence to meet these varying conditions, I use a slideable bearing, backed by a spring, so that the rear bearing may compensate for the varying conditions of the weather. 75

I have illustrated and described my invention in connection with a printing press having an impression cylinder and a reciprocating type-bed; however I do not confine my invention to this form of printing press or 80 machine, but wish to claim broadly its use in connection with any form of machine to which sheets are fed singly and to have the invention operated by any part of the machine that will rock the depending arm, regardless of whether such part reciprocates or rotates. I do not, therefore, confine myself to the particular form shown, but wish to use any means that will ratchet a bank of stock forward with means to make such 90 element inoperative. 85

Having thus described my invention, what I claim is:

1. In a printing press having an impression cylinder and a reciprocating type-bed, 95 the combination therewith of a feed-table mounted thereon, a main shaft journaled near the front end of said table, pulleys mounted upon said shaft, pulleys mounted near the rear end of said table, belts passing 100 around said table and upon said pulleys, a depending arm pivotally mounted and normally in the pathway of the type-bed with means to move said arm out of the pathway of said type-bed, connections between said 105 ratchet and the said depending arm.

2. In a printing press having an impression cylinder and a reciprocating type-bed, the combination therewith of a feed-table mounted thereon, a main shaft journaled 110 near the front end of said table, pulleys mounted upon said shaft, pulleys mounted near the rear end of said table, belts passing around said table and upon said pulleys, a depending arm pivotally mounted, a member pivotally attached to said depending arm and normally in the pathway of said 115 type-bed; a ratchet rigid upon said main-shaft, connections between said ratchet and said depending arm. 120

3. In a printing press having a reciprocating type-bed, the combination therewith of a feed-table mounted thereon, a main-shaft journaled near the front end of said feed-table, pulleys rigid upon said shaft, 125 pulleys mounted near the rear end of said feed-table, belts passing around said table and upon said pulleys, a depending arm pivotally mounted, a member pivotally attached to said depending arm and normally in the 130

pathway of said type-bed, a treadle pivotally mounted with suitable connections between said treadle and said pivoted member adapted normally to hold said member out 5 of the pathway of said type-bed, a ratchet upon said mainshaft, connections between said ratchet and the said depending arm. 4. In a printing press the combination of a feed-table mounted thereon, a member attached to said table, a threaded rod slidably mounted in said member, a spring mounted upon said rod, a set-nut upon said rod and contacting said spring, a tail-board attached to said feed-table, an arbor-bracket mounted 10 upon the said threaded rod and contacting 15

said tail-board, members attached to said tail-board to guide said arbor bracket, a pulley mounted in said arbor-bracket, a belt passing around said pulley.

5. In a printing press the combination of 20 a feed table mounted thereon, a member mounted closely adjacent the rear end on a plane above and parallel to said table, power-rotated pulleys journaled in said table, belts mounted upon said pulleys and passing be- 25 tween said table and said member.

JAMES G. HARDIE.
